Henderson, Tex.

Application March 29, 1941, Serial No. 385,812

3 Claims. (Cl. 121—164)

This invention relates to new and useful improvements in hydraulic lifting mechanisms.

One object of the invention is to provide an improved mechanism for operating the usual reciprocating well pump, which mechanism is actuated by a pressure fluid and is preferably located at the surface of the well, but which may be disposed below the surface.

An important object of the invention is to provide an improved hydraulic lifting mechanism, wherein a reciprocating piston which is arranged to operate a well pump is raised and lowered by a fluid pressure; the mechanism being so arranged that the piston exhausts the fluid on every other stroke thereof, whereby unnecessary dissipation of the pressure of said fluid is eliminated and the maintenance of the desired pressure is made possible with a minimum amount of power.

Another object of the invention is to provide an improved hydraulic lifting mechanism having means for counterbalancing the major portion of the load, whereby the load is substantially equal on both the upstroke and downstroke so as to require the same amount of power and also whereby the operation of the mechanism is more uniform and smoother.

A particular object of the invention is to provide an improved hydraulic lifting mechanism, of the character described, wherein the shock of the upstroke of the operating piston is eliminated by reducing the amount of pressure fluid admitted to said piston; there being other means provided for absorbing the shock of the downstroke of the piston.

A further object of the invention is to provide an improved hydraulic lifting mechanism wherein in the admission of pressure fluid to the piston is controlled by a snap-action valve which is actuated by the movement of said piston and which in turn controls the direction of movement or stroke of the piston by changing the direction of flow of the pressure fluid.

Still another object of the invention is to provide an improved hydraulic lifting mechanism which is operated by a closed pressure fluid system, the mechanism being so arranged that the small amount of fluid exhausted or displaced may be easily and readily returned to the source of supply, whereby an economical, efficient, reciprocal lifting mechanism is provided.

A still further object of the invention is to provide an improved hydraulic lifting mechanism, of the character described, which may be actuated by a central source of fluid pressure, whereby two or more mechanisms may be oper-

ated by one power unit so as to reduce operating and maintenance costs.

Yet, another object of the invention is to provide an improved hydraulic lifting mechanism, of the character described, wherein the counterbalancing means is so arranged that the same may be adjusted to compensate for fluctuations of the flow of the well fluid from the formation into the working barrel of the pump, whereby a smooth and uniform operation of the mechanism is assured.

A further object of the invention is to provide improved counterbalancing means for a hydraulic lifting mechanism which may be actuated by an artificial pressure fluid or by the pressure of well fluid which is within the well casing of the well being pumped.

A construction designed to carry out the invention will be hereinafter described together with other features of the invention.

The invention will be more readily understood from a reading of the following specification and by reference to the accompanying drawings, in which an example of the invention is shown, and wherein:

Figure 1 is a view, partly in elevation and partly in section, of a hydraulic lifting mechanism constructed in accordance with the invention.

Figure 2 is a view, similar to Figure 1, showing the mechanism in its position during the downstroke of its piston.

Figure 3 is a transverse, vertical, sectional view, on an enlarged scale, of the upper portion of the mechanism.

Figure 4 is a continuation of Figure 3, showing the central portion of the mechanism.

Figure 5 is a continuation of Figure 4, showing the lower portion of the mechanism.

Figure 6 is an enlarged, transverse, vertical, sectional view of the control valve, showing the same in its lowered position during the upstroke of the piston.

Figure 7 is a similar view of the valve in its raised position during the downstroke of the piston.

Figure 8 is a horizontal, cross-sectional view taken on the line 8—8 of Figure 7.

Figure 9 is a horizontal, cross-sectional view taken on the line 9—9 of Figure 7.

Figure 10 is an enlarged, transverse, vertical sectional view of the automatic cushioning control valve.

Figure 11 is a transverse, vertical, sectional view of a modified form of control valve,

Figure 12 is a schematic view, showing two lifting mechanisms connected to the same source of fluid pressure.

Figure 13 is a transverse, vertical, sectional view of a modified form of lifting mechanism.

Figure 14 is an enlarged, transverse, vertical sectional view of the modified mechanism, showing its piston at the end of its upstroke.

Figure 15 is an elevation of a modified form of counter-balancing apparatus, and

Figure 16 is a similar view of another form of counter-balancing apparatus.

This application is filed as a continuation-in-part of our copending application, Serial No. 225,504, filed August 18, 1938, now Patent No. 2,273,349.

In the drawings, the numeral 10 designates the usual well casing having a string of tubing 11 extending therethrough. The conventional pump rods 12 depend axially through the tubing and are connected to the plunger of a well pump (not shown), which is mounted in said tubing. The improved lifting mechanism A is arranged to be mounted at the surface of the well on suitable brackets or supports 13 above the customary flow T 14 and pump rod stuffing box 15.

The mechanism includes a short, upright cylinder 16, having an angular collar 17 welded or otherwise secured to its exterior adjacent its lower end, whereby it may be fastened by suitable bolts 18 to the brackets 13. The upper end of the cylinder 16 is connected by a stuffing box 19 to the lower end of an elongate, cylindrical sleeve 20 which is of substantially the same diameter so as to form a continuation thereof. A reduced, upstanding collar 21 is preferably made integral with the upper end of the stuffing box 19 and, as is clearly shown in Figure 4, the collar is of smaller diameter than the sleeve 20 and is disposed within its lower end. A cylinder 22 extends axially substantially throughout the length of the sleeve and has its lower end snugly engaging over the collar 21. The diameter of the cylinder 22 is smaller than the diameter of the sleeve 20 to provide an annular space 23 therebetween.

A piston 24 is mounted to reciprocate within the cylinder 22 and is connected to a counter-balance piston 26 slidably disposed within the cylinder 16 by an inter-connecting piston rod 25 which extends through the stuffing box 19. A coupling 27, carried by the upper end of the pump rods 12, fastens said rods to the depending rod 28 of the piston 26, whereby the rods 12 are connected to said piston and the piston 24. A reduced, depending skirt 29 is made integral with the lower end of the piston 24 and co-acts with one or more cushioning slots 30, formed in the lower end of the cylinder 22, to absorb the shock and to assure a smooth downstroke of said piston. The slots 30 are substantially key-shaped, being enlarged and circular at their upper ends, and establish communication between the bore of the cylinder 22 and the annular space 23.

For admitting fluid under pressure to the annular space 23, a suitable inlet pipe 31 is connected to the upper end of the sleeve 20. The pressure of this fluid is utilized to reciprocate the piston 24 so as to raise and lower the pump rods 12 and pump plunger (not shown) attached thereto for lifting the natural well fluid to the surface. In order to elevate the piston 24, the fluid pressure flows from the annular space 23 through the slots 30 into the cylinder 22 beneath

said piston. After the piston has completed its upstroke, the pressure of the fluid will be exerted upon the upper end of said piston to force the same downwardly. It is pointed out that the end portion of the downstroke of the piston will be cushioned by the co-action of the slots 30 and the skirt 29 of said piston. As the downstroke begins, the piston moves downwardly in its cylinder and the skirt thereof forces the fluid therebelow from the cylinder through the slots 30. Since the enlarged upper ends of the slots are wide open, there is substantially no restriction of the escaping fluid at this time, with the result that the downward movement of the piston at the start of the downstroke is comparatively rapid. This comparatively rapid downward movement continues until the skirt 29 moves opposite the upper ends of the slots and, as soon as this occurs, the skirt co-acts with the slots to reduce the cross-sectional area of the slots 30, and thereby restrict the escape of fluid. This restriction of the escaping fluid causes the lowering of said piston and pump rods attached thereto to be gradually slowed until the piston and rods finally stop at the end of the downstroke. Thus, smooth operation is assured. It is noted that the cross-sectional area of the cushioning slots controls the speed of descent at the lower portion of the downstroke and that the time of the downstroke may be regulated, to an extent, by varying the area or size of said slots.

The upper end of the sleeve 20 is screw-threaded onto a reduced collar 32 which depends from an annular valve body 33, the body having its upper end connected to the lower end of an elongate cap or housing 34 by a suitable coupling 35. The valve body 33 is provided with an axial bore 36 which has its lower extremity enlarged as shown at 37. A tubular valve member 38 is slidable in the bore 36 and is formed with an external, radial flange or shoulder 39 adjacent its lower end as shown in Figure 6. The lower portion of the valve member 38 below the flange 39 is preferably reduced in diameter and the enlarged undersurface of said flange is bevelled to provide an amplified seating surface 40.

An upstanding collar 41, complementary to the collar 32 of the valve body 33, is screw-threaded into the upper end of the cylinder 22 and engages within the bore of said collar 32 as shown in Figures 6 and 8. The upper end of the collar 41 is internally screw-threaded so as to receive a valve seat 42 which is complementary to and is arranged to be engaged by the bevelled surface 40 of the valve member 38 (Figure 6). In order to establish communication between the enlarged bore 37 of the valve body 33 and the annular space 23 and inlet pipe 31, a plurality of angular slots or openings 43 are formed in the peripheral upper portion of the collar 41 (Figure 8). A collar 44 is screw-threaded into the lower end of the coupling 35 and depends within the bore 36 of the valve body to provide a valve seat which is arranged to be engaged by the upper end of the valve member 38, as is clearly shown in Figure 7. Immediately below the collar 44, an enlarged annular groove or channel 45 is formed in the bore 36 of the valve body and this groove communicates with a suitable outlet or exhaust pipe 46.

When the valve member is in engagement with the seat 42, its upper end is spaced from the seat 44 and a flow of pressure fluid from the annular space 23 between the cylinder 22 and sleeve 20

into the upper end of said cylinder is prevented. However, the fluid within the annular space 23 may flow through the cushioning slots 30 into the lower end of the cylinder so as to lift the piston 24 (Figure 2). As the valve member moves upwardly from the seat 42 to engage the seat 44, communication between the annular space 23 and the upper end of the cylinder bore is established by means of the slots 43 and the enlarged bore 37 of the valve body. When the valve member is in its raised position engaging the valve seat 44 (Figure 7), the groove 45 and pipe 46 are closed to prevent an escape of the pressure fluid flowing through the slots 43 and enlarged bore 37 into the upper end of the cylinder 22. As is clearly shown in Figure 2, the fluid entering the upper end of the cylinder is applied to the piston 24 so as to force the same downwardly. To effect the escape of the fluid between the valve member and the seat 44 on the upstroke of said member, the extreme upper end of the same is reduced in diameter as shown at 41 to provide an annular space or clearance between the member and the bore 36 of the valve body, whereby fluid may bleed into the groove 45 and pipe 46. This arrangement obviates the possibility of a pressure remaining above the valve member 38 and assures that the pressure below said valve will hold the same in engagement with the seat 44. It is pointed out that the depending portion of the valve member below the seating surface 40 has a snug sliding fit within the bore of the collar 41 and not only serves as a guide for said member but also tends to maintain said collar bore closed after said seating surface has moved away from its seat 42 until the groove 45 and pipe 46 have been substantially closed by the upper portion of the member. Thus, no appreciable quantity of fluid is admitted into the upper end of the cylinder until after the shutting off of the exhaust pipe and groove, whereby unnecessary discharge of fluid is avoided and the occurrence of a balanced condition prevented.

From the foregoing, it is readily apparent that the valve member 38 controls the admittance to and exhaust of fluid from the interior of the cylinder 22 and, as explained, this fluid is under pressure so as to actuate the piston 24. A piston rod 48, of less diameter than the rod 25, is connected to the upper end of the piston and extends axially through the cylinder 22, tubular valve member 38 and elongate cap 34. For guiding the piston rod axially through the valve member 38, the upper and lower ends of said member are provided with a plurality of internal, radial ribs or projections 49 which are spaced equidistant as shown in Figure 9. A guide member 50, having radial wings 51, is mounted on the upper end of the piston rod 48 to aid in axially guiding said rod in its movement.

For sliding the valve member 38 from one position to the other to reciprocate the piston 24, as has been hereinbefore described, an elongate sleeve 52 is slidably mounted on the upper end of the piston rod adjacent the guide member 50, being supported by a collar 53 which is secured to said rod (Figure 3). The upper end of the sleeve 52 telescopes the lower end of a second elongate sleeve 54 which surrounds the rod. A coiled spring 55 surrounds the rod and is disposed within the lower sleeve 52, with its upper end engaging the lower edge of the upper sleeve 54. The lower end of the spring 55 rests upon an internal, annular shoulder 56 formed at the

lower end of the lower sleeve and exerts its pressure to constantly urge the telescoping sleeves apart. Separation of the sleeves 52 and 54 is prevented by a collar 57 carried by the rod and, obviously, the spring 55 normally holds the upper sleeve 54 in engagement with the collar 57 as shown in Figure 3. As shown in Figure 7, the extreme lower end of the sleeve 52 is enlarged as shown at 58, while an annular flange 54a is formed on the upper extremity of the sleeve 54 (Figure 3). The telescoping sleeves 52 and 54 are utilized to lower the valve member 38 at the completion of the downstroke of the piston 24, as will be hereinafter explained.

For raising the valve member at the completion of the upstroke of the piston, an elongate sleeve 59, similar to the sleeve 54, is slidable on the lower end of the piston rod 48 above said piston (Figures 3 and 4), being supported by a collar 60 which is secured to said rod. The upper end of the sleeve 59 is telescoped by the lower end of a second elongate sleeve 61, which is similar to the sleeve 52. A coiled spring 62 is confined within the bore of the sleeve 61 between the upper end of the sleeve 59 and an internal, annular shoulder 63 formed at the upper end of said sleeve 61. The spring urges the upper end of the sleeve 61 into engagement with a collar 64 carried by the piston rod 48, whereby said sleeve and the sleeve 59 are constantly urged apart. The upper extremity of the sleeve 61 is enlarged to form an external, annular shoulder 65 as shown in Figure 6. An annular flange 59a, similar to the flange 54a of the sleeve 54, is formed on the lower end of the sleeve 59 and, normally, engages the collar 60 as shown in Figure 4.

With the piston 24 at the lower end of its downstroke, the parts are in the position shown in Figures 3 to 5, and, in such position, the enlarged portion 58 of the sleeve 52 is engaging the upper internal ribs 49 of the valve member 38. The collar 53 is within the axial opening formed by the ribs and is spaced from the sleeve, having been moved to this position on the lowering of the valve member, which lowering has just previously occurred. The pressure fluid within the annular space 23 may flow through the slots 30 into the lower end of the cylinder 22 to raise the piston 24, as has been hereinbefore explained. As the piston moves upwardly, the piston rod 48 travels therewith, thereby raising the sleeve 52 away from the upper ribs of the valve member. The pressure of the spring 55 moves the sleeve immediately into contact with the collar 53 and said sleeve remains in this position until the downstroke is completed.

As the upstroke continues, the sleeves 52 and 54 are moved upwardly away from the valve member, while the sleeves 59 and 61 are moved toward said member. During the upstroke, the pressure of the fluid is acting against the effective cross-sectional area of the valve member, this area being the upper surface of the external flange 39. Thus, the member 38 is held in its lowered position engaging the seat 42 as shown in Figure 6. As the piston approaches the end of its upstroke, the collar 64 above the sleeve 61 enters the axial opening formed by the lower internal ribs 49 of the valve member and the external shoulder 65 of said sleeve engages said ribs (Figure 6). When this occurs, further movement of the upper sleeve 61 is resisted by the pressure of the fluid holding the valve member seated, and continued upward movement of the piston 24 and its rod 48 causes an upward movement or telescoping of the lower

sleeve 58 relative to said upper sleeve. This results in a compression of the coiled spring 62 confined between the sleeves, which spring is acting to urge the sleeve 61 upwardly. This compression of the spring continues until the annular flange 59a of the sleeve 58 engages the lower end of the sleeve 61, whereby the full force of the fluid pressure is exerted against the lower end of the valve member. Since the lower end of the piston 24 is of greater cross-sectional area than the upper end of the valve member, the fluid pressure will move said member upwardly away from its seat 42. As soon as this occurs, the tension of the compressed spring is added to the fluid pressure to rapidly move the valve member upwardly into engagement with the seat 44, whereby a snap action is imparted to the movement of said member.

As soon as the valve member is moved to its raised position (Figure 7), the valve seat 42 is uncovered to permit the pressure fluid to flow from the annular space 23, through the slots 43 and enlarged bore 37 into the upper end of the cylinder 22 to force the piston 24 downwardly. Since the lower end of the rod 25 is not exposed to the fluid pressure as is the upper end of the rod 48, the effective cross-sectional area of the upper end of the piston is greater than that of its lower end. Thus, when both ends of the piston are exposed to the pressure of the fluid, said piston will be lowered. It is pointed out that during the upward movement of the valve member, the depending portion of said member which engages within the bore of the collar 41 maintains the same closed to prevent fluid from entering the cylinder 22 until the exhaust pipe 46 and groove 45 are closed by the upper end of the member. During the downstroke of the piston, the valve member is held in its raised position by the pressure exerted against and acting upon the lower end of said member.

The downstroke of the piston 24 and its rod 48 continues until the lower end of the sleeve 52 strikes the upper internal ribs of the valve member and the coiled spring 55 is compressed so as to permit the annular flange 54a of the sleeve 54 to engage the upper end of said sleeve 52. When this occurs, the member 38 is returned to its lowered position by the force of the fluid pressure exerted against its upper end and the compression of the spring 55 to again shut off communication between the annular space 23 and the upper end of the cylinder bore, whereby the pressure of said fluid will be exerted against the lower end of the piston to raise the same. It is noted that the downstroke of the piston will be cushioned by the co-action of the depending skirt 29 of said piston and the cushioning slots 30. The provision of the telescoping sleeves above and below the valve member 38 makes it possible to operate said member with a snap action and thereby effect a change in the direction of movement of the piston 24.

For aiding the snap action of the valve member and for holding the same in its raised and lowered positions, a frictional resistance in the form of a spring-pressed ball 66 is mounted in a radial opening 67 formed in the upper end of the valve body 33. The ball is arranged to engage an annular groove 68 formed in the exterior of the valve member intermediate its ends, as is clearly shown in Figure 6. It is manifest that the frictional resistance occasioned by the engagement of the ball 66 in the groove 68 must be overcome before the valve member may be moved upwardly and, thus, this frictional resistance is added to the pressure acting downwardly on the upper surface

5 of the external flange 39 of said member and resisting upward movement of the member by the coiled spring 62. A second annular groove 69, below the groove 68, receives the ball 66 after the valve member has been moved to its raised position (Figure 7) to aid in the resistance of the downward movement of said member. However, it is noted that the spring-pressed ball 66 may be omitted as the snap action arrangement which is assisted by this frictional resistance is unessential to the operation of the valve member. It is also possible to dispense with the telescoping sleeve below the valve member.

From the foregoing, it is readily apparent that the piston 24 is reciprocated in the cylinder 22 by an auxiliary pressure fluid, the introduction of which is controlled by the valve member 38. For conducting the pressure fluid to the inlet pipe 31 and the annular space 23, a suitable pipe 70 is connected to said pipe 31 and leads to a source of supply (not shown). The exhaust pipe 46 also communicates with the source of supply by means of a pipe 71, whereby the fluid exhausted from the lifting mechanism may be returned to said source. A control valve 72 is mounted in the pipe 70 for regulating the amount of fluid admitted to the annular space 23 and includes a valve body 73 having a transverse partition 74 formed therein, as shown in Figure 10. The partition is provided with an opening 75 within which a cylindrical valve member or plunger 76 is movable. A diametrically-extending notch or slot 77, which is V-shaped, is formed in one end of the plunger 76, and, manifestly, as the plunger is reciprocated within the opening 75, more or less of the slot is exposed to the flow of fluid, whereby the flow area through said opening and past the partition 74 is controlled. A valve stem 78 is connected to the other end of the plunger 76 and extends laterally from the valve body 73 so that it may be connected by a coupling 79 to an operating rod 80 which projects into the cylinder 16 of the lifting mechanism. Suitable stuffing boxes 81 and 82 surround the valve stem 78 and operating rod 80, respectively. The inner end of the rod 80 is provided with a roller or wheel 83 which is spaced from the exterior of the piston rod 25 of the counterbalance piston 26 (Figure 4). A collar 84 is adjustably mounted on the rod 25 above the piston and is provided with an annular, upwardly and outwardly inclined surface 85 so as to serve as a cam for actuating the rod 80. When the piston 26 moves to its upper position, the roller 83 of the rod 80 will be engaged by the bevelled surface 85 of the collar 84, whereby said roller will ride upon said collar so as to gradually force said rod and the plunger 76 to the position shown in Figure 2.

With the plunger 76 in the position shown in Figures 1 and 10, the inner portion of the V-notch or slot 77 is exposed to the fluid and a flow of fluid through the opening 75 is permitted. In this position, the fluid flowing through the slot from the line 70 is substantially unrestricted as the area of the slot is substantially the same as the cross-sectional area of the line. If the plunger is moved through the opening to the left in Figure 10 by the cam collar 84 engaging the roller 83 of the rod 80, flow through the valve will be restricted and partially shut off as shown in Figure 2. By adjusting the coupling 79, the combined length of the stem 76 and rod 80 may be varied to alter the by-pass area of the notch 77 and thereby vary the quantity of fluid flowing through the opening 75 of the valve body. A nut

86 may be screw-threaded onto the outer end of the rod 80 so as to engage the housing of the stuffing box 82 and limit the movement of said rod toward the rod 25. It is pointed out that since the plunger 76 is constantly exposed to the fluid, the pressure of said fluid is utilized to move and maintain said plunger in its open position when the roller is not in engagement with the cam collar.

When the piston 24 is in its lowered position, the parts of the valve 72 will be in the position shown in Figures 1 and 10 to permit a substantially unrestricted flow of fluid through the body 72 of said valve to the pipe 31, annular space 23 and cylinder 22 to raise said piston. As the piston approaches the end of its upstroke, the bevelled surface 85 of the upwardly moving collar 84 will engage the roller 83 of the rod 80 to force the plunger 76 outwardly to the left in Figure 1. Due to the V-notch or slot 77, flow through the valve body will be gradually restricted so as to decelerate the speed of the upstroke of the piston. When the piston reaches the upper end of its stroke, the plunger 76 will have been moved to the position shown in Figure 2 to restrict and partially cut off the flow of fluid through the valve body so as to cushion the upstroke of said piston. Thus, the upstroke of the piston is cushioned to prevent the occurrence of a shock or jar. As soon as the roller 83 is disengaged from the collar 84, the pressure of the fluid will move the plunger 76 to its open position to permit an increased flow through the flow to the annular space 23. Obviously, this increased flow will accelerate the downwardly moving piston. Since it is virtually impossible to accurately adjust an automatic valve of the type herein described, a small tube 87 is connected in the pipe 70 and bypasses the valve 72 for conducting a predetermined amount of pressure fluid to the annular space 23. The by-pass tube, which has a manual control valve 88 mounted therein, may be used for fine adjustments or may be put into use to compensate for wear in the valve 72 or some of its parts.

The lower end of the cylinder 16 is connected by a swaged coupling collar 89 to a T 90 which has a stuffing box 91 depending therefrom for packing off around the pump rods 12. The T 90 communicates with the pipe 70 through a small tube 92, having a hand valve 93 mounted therein for admitting the pressure fluid to the cylinder 16. A suitable tank 94 is also connected to the T by means of a pipe 95, having suitable hand valves 96 and 97 mounted therein, and air under pressure is preferably stored in the tank. For lubricating the counterbalance piston 26 and the bore of the cylinder 16, a predetermined fluid or liquid level is maintained in the tank 94 as shown by the dotted line in Figures 1 and 2. This fluid may be introduced into the tank from the pipe 70 by means of the tube 92 and pipe 95. After the desired quantity has been admitted to the tank, the valve 93 is closed to shut off the flow or adjusted to permit the feeding of a few drops per minute, whereby any slippage of fluid past the piston is compensated.

The air within the tank 94, which is exerted against the underside of the piston 26, is preferably maintained under a pressure sufficient to balance the weight of the sucker rods 12 and pump plunger (not shown) as well as one-half of the weight of the natural fluid or load being lifted by said plunger. Therefore, in order to lift the operating piston 24, only sufficient pres-

sure fluid to overcome or lift one-half of the weight of the fluid column or load is required. On the downstroke of the piston 24, the pressure of the fluid is the same and need be only sufficient to overcome that portion of the air pressure in excess of the weight of the sucker rods and pump plunger, since the remainder of said air pressure offsets or is balancing said rods and plunger. Due to the provision of this counterbalancing apparatus, a low operating pressure may be utilized to actuate the piston 24, whereby the natural fluid may be economically lifted to the surface. Obviously, since the same pressure or force is employed in lowering the piston 24 as in raising the same, a smooth uniform operation or reciprocation thereof is assured with minimum wear.

In order to accommodate fluctuations in the volume or weight of the fluid column being lifted by the pump plunger, a by-pass pipe 98 is connected in the pipe 95 between the valve 97 and T 90 on either side of the valve 96. A check valve 99 is mounted in the by-pass pipe 98 for preventing a flow of the counterbalancing fluid from the tank 94 to the cylinder 16 and for permitting an unrestricted flow in the opposite direction from said cylinder to said tank. Due to the provision of the by-pass pipe and check valve, the valve 96 may be adjusted to restrict the flow of the counterbalancing fluid through the pipe 95 so as to control the rate of such flow. Thus, the fluid may be introduced into the cylinder 16 upon the upstroke of the piston 26, at a predetermined rate, whereby the speed or rate of movement of the piston on the upstroke is controlled. Upon the downstroke of the counterbalancing piston, since the check valve 99 permits an unrestricted flow to the tank 94, the fluid will be exhausted from the cylinder 16 into said tank against the predetermined pressure therein, whereby the downward movement of said piston is controlled in accordance with such pressure. Thus, the rate of movement of the upstroke is controlled by the adjustment of the valve 96, while the downstroke is controlled by the counterbalancing pressure in the tank, and therefore, the speed of operation of the piston may be accurately controlled, regardless of well loads. Manifestly, this arrangement makes possible a smoother and more uniform operation of the mechanism irrespective of varying fluid columns or loads lifted by the pump plunger.

A lateral exhaust pipe 100 connects the upper end of the cylinder 16 to the pipe 71 and has a check valve 101 mounted therein, whereby any fluid or air that accumulates within said cylinder above the piston 26 may be expelled therefrom on the upstroke of said piston. To prevent the formation of a vacuum within the upper end of the cylinder, an air inlet valve 102 is connected in the pipe 100 so that air may be drawn into said cylinder on the downstroke of the piston 26. A suitable manual control valve 103 is mounted in the pipe 70 intermediate the tubes 87 and 92, while a similar valve 104 is located in advance of said tube 92. For bleeding off air or gas pressure which might accumulate within the elongate cap or housing 34, a small tube 105 establishes communication between said housing and the exhaust pipe 71. A hand valve 106 is connected in the tube so that the pressure within the housing may be bled into the pipe 71 immediately prior to the operation of the lifting mechanism and then closed during such operation.

In operation, a pressure fluid is introduced into the annular space 23 by means of the pipe 70 and 31 and, since the parts are in the position shown in Figure 1 and Figures 3 to 5, the fluid will flow through the cushioning slots 30 into the lower end of the cylinder 22. The pressure of this fluid acts against the underside of the piston 24 to move the same upwardly in its cylinder with the result that the piston rods 48 and 25 secured to said piston, as well as the counterbalance piston 26 connected to the rod 25, are raised. The lifting of the piston 26 causes the sucker rods 12 and pump plunger to be moved upwardly also since they are secured thereto by the rod 28. Toward the end of the upstroke of the piston, flow through the opening 75 of the valve 72 is restricted by the plunger 76 so as to decelerate the speed of the movement of said piston.

However, upward movement of the piston 24 continues until the sleeve 61 which is carried by the rod 48 strikes the underside of the lower internal ribs 49 of the valve member 38. As has been hereinbefore explained, this engagement causes the spring 62 to be compressed and the sleeve 61 to telescope the sleeve 59, whereby the flange 59a contacts the lower end of said sleeve 61 to directly transmit the force of the fluid pressure exerted against the lower end of the piston 24 to the lower end of the valve member. When this pressure overcomes the pressure acting downwardly on the flange 39 as well as the frictional resistance of the spring-pressed ball 66, the valve member is moved away from the seat 12 to its upper or raised position (Figure 7), and such upward movement will be accelerated by the compression of the spring 62. Any fluid between the valve member and the seat 44 may bleed into the groove 45 and pipe 46 on the upward movement of said member due to the reduced diameter of the extreme upper end 41 of said member. With the valve member in this position, its upper end will engage the seat 44 and communication between the annular space 23 and the upper end of the cylinder 22 is established. At the same time, the co-action of the cam collar 85 and the roller 83 of the rod 80 moves the plunger outwardly to substantially close the opening 75 of the valve 72 as shown in Figure 2, whereby a restricted flow of fluid enters the space 23 through the reduced opening of said valve and the tube 87. Thus, the end of the upstroke of the piston is cushioned.

The reduced flow of fluid to the space 23 will enter the upper end of the cylinder 22 by means of the slots 43 and the enlarged bore 37 of the valve body, whereby the pressure of said fluid will be exerted against the upper surface as well as the underside of the piston 24. Since the effective cross-sectional area of the upper surface of the piston is greater than the underside thereof, the pressure of the fluid acting against the underside will be nullified. Whenever the pressure of the fluid is sufficient to overcome the air pressure utilized as a counterbalance, the piston 24 will be forced to its lowered position. As the piston 24 moves downwardly, it is obvious that a downward movement will be imparted to the plunger of the pump due to the connection therebetween. As soon as the roller 83 of the rod 80 is disengaged from the collar 84, the pressure of the fluid in the pipe 70 will actuate the plunger 76 to fully open the valve 72 (Figure 10) and permit an increased flow to the piston 24. Thus, the speed of the downward

movement of the piston will be accelerated. However, the end of the downstroke of the piston will be cushioned by the co-action of the depending skirt 29 of said piston and the cushioning slots 30.

The valve member 38 remains in its raised position until the sleeve 52 on the piston rod 48 engages the upper internal ribs of said member (Figure 7). When the sleeve strikes the ribs 10 and the piston rod continues its downward movement, the spring 55 confined within said sleeve is compressed, and the flange 54a moved into engagement with the lower end of the sleeve by the same telescoping the sleeve 54. Thus, 15 the force of the fluid pressure acting downwardly on the piston 24 is applied directly to the upper end of the valve member to overcome the frictional resistance of the spring-pressed ball 66 and the pressure exerted against the lower end of said valve member, whereby the latter is again lowered so that its seating surface 40 will engage the seat 42 and shut off flow through the slots 43 into the upper end of the cylinder 22. The pressure of the fluid will then be exerted 20 solely against the lower surface of the piston 24 so as to again move the same upwardly, whereby the operation is repeated. It is noted that although the hereinbefore described hydraulic lifting mechanism A is fully reciprocating, that 25 is, raised and lowered by a pressure fluid, the same only exhausts on the upstroke thereof, whereby the valve mechanism is simplified. It is also pointed out that the lifting mechanism could be positioned within the bore of a well by 30 disposing the various parts in concentric conductors.

In Figure 11, a modified form of control valve is shown and said valve may be mounted in the mechanism at the same point as has been hereinbefore described. The valve includes a valve body 133, similar to the valve body 33, which is connected by the coupling 35 to the housing 34 and has its depending collar 132 screw-threaded into the upper end of the sleeve 20. An axial bore 136 extends vertically through the valve body and is provided with enlarged counterbores 134 and 137 at its upper and lower ends. A valve member 138, similar to the valve member 38, is 45 slideable in the bore 136 and has its lower end internally screw-threaded to receive a collar 139. An external, radial flange or shoulder 140 is formed on the lower end of the collar to provide a seating surface.

A collar 141, similar to the collar 41, is screw-threaded into the upper end of the cylinder 22 and engages within the bore of the depending collar 132. The bore of the collar 141 is enlarged at its upper end so as to be of substantially the same diameter as the flange 140 of the collar 139, whereby said flange has a snug sliding fit within the enlarged portion of the bore and engages an annular valve seat 142 screw-threaded therein. To establish communication between the annular space 23 and the lower counterbore 137 of the valve body, angular flow slots or openings 143 are formed in the upper peripheral portion of the collar 141.

An annular, upstanding flange 135, of slightly less diameter than the upper counterbore 134 of the valve body, is preferably made integral with the external upper end of the valve member 138, whereby the annular space between the flange and said counterbore permits fluid pressure above said valve member to bleed into the groove 45 and pipe 46 in the same manner as the

reduced upper end 47 of the valve member 38. The flange 135 is arranged to engage a valve seat 145 formed by a collar 144 which is screw-threaded into the lower end of the coupling 35. A flange 146, complementary to the flange 135, depends from the collar 144 and engages within said flange 135 when the valve member is moved upwardly to its raised position. When the member 138 is in this position, the upper end of the flange 135 will engage the valve seat 145 and the upper end of said member will be engaged by the flange 146 to shut off communication between the groove 45 and the bore of the member. It is pointed out that the flange 140 of the collar 139, which has a snug sliding fit within the bore of the collar 141, does not move out of engagement with said bore until the flange 135 of the valve member has engaged the flange 146 to close the bore of said member. Thus, no fluid is admitted into the upper end of the cylinder 22 through the annular space 23, slots 143 and counterbore 137 until after the exhaust pipe and groove have been shut off, whereby the occurrence of a balanced condition is obviated.

For raising the valve member 138, a short sleeve 147 is slidably mounted on the piston rod 48 and is confined between the collars 60 and 64 which are positioned in close proximity to each other. An external, annular flange 148, of substantially the same diameter as the bore of the collar 141, is preferably made integral with the upper portion of the sleeve for engaging the collar 139 of the valve member. The diameter of the flange 148 is such that when the same is in engagement with the valve member, the bore of said member is closed to prevent the passage of fluid pressure thereinto. The upward movement of the valve member 138 by the sleeve 147 is substantially the same as the upward movement of the valve member 38 by the telescoping sleeves 59 and 61, hereinbefore described in the first form, with the exception that there is no frictional resistance to such movement nor any spring for imparting a snap action to said valve member. However, the telescoping sleeves 52 and 54 and coiled spring 55 are employed to move the valve member 138 from its upper to its lower position in exactly the same manner as in the first form. The internal, radial, guide ribs 49 are formed within the upper end of the valve member and within the collar 139 which is screw-threaded into the lower end of said member.

During the upward movement of the piston 24, the seating surface of the flange 140 of the valve member will be held in engagement with the valve seat 142 by the fluid pressure exerted against the upper end of said member. Due to the provision of the flange 135, the effective cross-sectional area of the upper end of the valve member is greater than the small portion of the lower end of said member exposed to the fluid pressure. When the valve member is in its raised position with the upper end of the flange 135 engaging the valve seat 145 and the lower end of the flange 146 engaging the upper end of said member, the effective cross-sectional area of the lower end of the member will be greater than that of its upper end. Thus, the fluid pressure maintains the member 138 in its raised and lowered positions and in snug engagement with the valve seats 142 and 145 until the position of said member is changed by the reciprocation of the piston 24 and its rod 48.

If desired, the valve member 138 may be raised by the telescoping sleeves 59 and 61 and the coiled

spring 62 in place of the short sleeve 147 without affecting the operation of said valve member. It is noted that a plurality of hydraulic lifting mechanisms may be connected to a single source of fluid pressure instead of providing a separate source for each mechanism. As shown in Figure 12, lifting mechanisms A and B may have their fluid inlet pipes 70 communicating with a suitable pump 107 by means of a line 108. The pump is driven by a suitable engine 109 and is supplied with fluid from a reservoir 110. The fluid exhausted from the mechanisms through the pipes 71 is conducted to the reservoir by a line 111. Manual control valves for controlling the flow of fluid through the lines may be provided at various convenient points.

In Figures 13 and 14, a slightly modified form of lifting mechanism is shown and includes the cylinder 20 within which the cylinder 22 is supported by the reduced, upstanding collar 21 of the stuffing box 19. A hollow piston 124, similar to the piston 24, is slidably disposed within the cylinder 22 and is connected to the counterbalancing piston 26 by a depending, tubular piston rod 125 which is screw-threaded into the lower end of the axial bore 126 of the piston, whereby the bore of the rod communicates with the bore of said piston. The bore 126 also communicates with the cylinder 22 above the piston by means of a plurality of upwardly and outwardly inclined, radial ports 127. The lower end of the piston is reduced in diameter as shown at 129 and is arranged to co-act with the cushioning slots 30 of the cylinder 22 to absorb the shock of the down-stroke of said piston in the same manner as the skirt 29 of the piston 24.

A valve body 112, similar to the valve body 33, has its reduced, depending collar 113 screw-threaded into the upper end of the sleeve 20 and is provided with an axial bore 114, the intermediate portion of which is reduced to form a counterbore 115. A tubular valve member 116, similar to the valve member 38, is slidable in the counterbore 115 and has a similar radial flange or shoulder 117 formed on its exterior adjacent its lower end. To provide an amplified seating surface, the underside of the flange is bevelled, as shown at 118, complementary to the valve seat 42 of the collar 41 which is screw-threaded into the upper end of the cylinder 22. A removable sleeve 119 is interposed between the valve member 116 and the counterbore 115, whereby undue wear of said counterbore is prevented. The angular slots 43 formed in the peripheral upper portion of the collar 42 establish communication between the lower end of the bore 114 of the valve body and the annular space 23.

The upper end of the valve body 112 is connected by a coupling 120, similar to the coupling 35, to the lower end of a short cap or housing 121. A collar 122, having an annular groove 123 formed in its under-surface, is screw-threaded into the lower end of the coupling 120 and depends within the upper end of the bore 114 of the valve body, whereby its groove provides a valve seat which is adapted to be engaged by the upper end of the valve member 116 as shown in Figure 14. The inner peripheral lower end portion of the collar 122 terminates a short distance above the lower end of said collar to form an annular, internal flange 128. Since the external diameter of the flange 128 is slightly less than the internal diameter of the bore of the valve member 116, an annular space or clearance is provided therebetween to permit the escape of fluid trapped be-

tween said member and the collar 122 upon the upward movement of the member. Obviously, the fluid within the upper end of the bore 114 may be displaced into the pipe 46 which communicates therewith upon the upstroke of the valve member.

It is manifest that this valve member controls the admittance to and exhaust of fluid from the cylinder in the same manner as the valve members 38 and 138 and that the pressure of this fluid actuates the piston 124 in the same manner as the piston 24. A piston rod 130, of less diameter than the bore 126 of the piston, extends axially through said bore, the tubular rod 125, the valve member 116 and through the housing 121. For guiding the piston rod 130 axially through the valve member, a plurality of internal, radial ribs 131 are provided at the upper end of said valve member. The piston rod is slidably connected to the piston by means of a flanged bushing 149 which is screw-threaded into the upper end of the bore of said piston and a nut 150 carried by the lower end of said rod. Since the nut 150 is of a diameter greater than that of the bore of the bushing 149, through which the piston rod extends, it is obvious that said rod may not be disconnected from the piston without removing said nut or bushing. A sleeve 151, having an external, radial shoulder or flange 152 formed on its upper end, is screw-threaded into the upper end of the flanged bushing 149 and surrounds the piston rod 130 which is slidable through its bore. The upper end of the piston rod projects through a stuffing box 153 screw-threaded into the top of the housing 121 and this stuffing box co-acts with the sleeve 151 and ribs 131 of the valve member to maintain said rod axially disposed.

For raising the valve member, a short sleeve 154 is slidably mounted on the sleeve 151 between the flange 152 of said sleeve and a collar 155 positioned adjacent the upper end thereof. The sleeve is very similar to the sleeve 147 (Figure 11) and has a similar external, annular flange 156 made integral with its upper end for engaging the lower end of the valve member. The diameter of the flange 156 is greater than the diameter of the bore of the valve member, whereby said bore is closed to prevent the passage of pressure fluid thereto when said flange is in engagement with the lower end of said member. The upward movement of the valve member 116 by the sleeve 154 is exactly the same as the upward movement of the valve member 138 by the sleeve 147, since the sleeve 151 which carries said sleeve 154 is connected to and is movable with the piston 124. The valve member 116 is moved from its upper to its lower position by the telescoping sleeves 52 and 54 and coiled spring 55 in substantially the same manner as the valve members 38 and 138, as has been hereinbefore described, with the exception that the lower end of the bushing 149 must engage the nut 150 carried by the piston rod 130 before said sleeves and spring will effect the downward movement of said valve member 116. Thus, the desired downward movement of the piston 124 relative to the valve member and piston rod is permitted, with the result that said rod and the housing 121 may be of materially less length than the piston rod 48 and housing 34 of the first form.

In order to prevent the formation of a fluid seal between the lower end of the bushing 149 and the upper surface of the nut 150 when the same are in engagement, a plurality of radial grooves or recesses 157 are formed in the lower end of said bushing, thereby eliminating the pos-

sibility of said nut adhering to the bushing. As has been hereinbefore explained, the piston rod 130 and its nut 150 remain stationary during the downward movement of the piston 124 until said nut is engaged by the bushing 149, whereby the nut, in effect, moves upwardly through the bore of the tubular piston rod 125 and the bore 126 of said piston. Due to the provision of the ports 127 in the piston, a portion of the fluid within the bore of the rod 125 and the bore of said piston above the nut 150 will be discharged into the cylinder 22 above the piston by the relative upward movement of said nut so as to prevent resistance to such relative movement. However, the chief function of the ports 127 is to by-pass the fluid displaced from the rod and piston bores to the cylinder upon the upward movement of the piston and rod relative to the nut and piston rod 130. It is pointed out that the operation of the valve member 116 would not be materially affected if the same was actuated by the mechanisms of the valve members 38 and 138 instead of the particular mechanism which has been hereinbefore described. It is also manifest that the valve members 38 and 138, if desired, may be actuated by the mechanism of the valve member 116.

In many instances, it may be desirable to utilize the gas or other pressure within the well casing to counterbalance the lifting mechanism in place of the air pressure as shown in Figure 15. In this event, a small tank 158 is substituted for the tank 94 and has its upper end connected by a pipe 159 to the flow outlet 160 of a casing head 161 mounted on the upper end of the well casing 10. Thus, communication is established between the interiors of the tank 158 and casing 10, whereby the gas pressure within said casing may be exerted upon the liquid within said tank in exactly the same manner as the air pressure. For controlling the pressure of the gas delivered to the tank, a suitable pop-off valve 162 is mounted in the pipe 159. A manual control valve 163 is also connected in the pipe between the pop-off valve 162 and the flow outlet 160. In some wells, the well fluid will be standing within the casing in relatively close proximity to the surface, with the result that there will be an accumulation of gas within the upper portion of said casing above the fluid level. Usually, this gas will be under a pressure sufficient to be utilized for counterbalancing the lifting mechanism, although such pressure is insufficient to force the well fluid up the tubing. In the event no pressure is present within the casing, a packer (not shown) may be inserted within the casing so as to seal off the annular space between the tubing and said casing and form an annular chamber thereabove. An auxiliary pressure may then be introduced into the annular chamber or the upper portion of the casing through the flow outlet 160 of the casing head 161, whereby such pressure may be employed to counterbalance the lifting mechanism.

As shown in Figure 16, the tank 158 may be eliminated entirely by connecting the pipe 159 directly to the pipe 95. In this instance, the lubricating liquid would be dispensed with and the pressure of the gas would be exerted directly against the underside of the counterbalancing piston 26.

The foregoing description of the invention is explanatory thereof and various changes in the size, shape and materials, as well as in the details of the illustrated construction, may be made,

within the scope of the appended claims, without departing from the spirit of the invention.

What we claim and desire to secure by Letters Patent is:

1. A hydraulic lifting mechanism including, a cylinder, a piston arranged to reciprocate within the cylinder having its lower end exposed to a pressure fluid for raising the same, an annular sleeve valve forming a continuation of said cylinder and adapted to expose the upper end of the piston to the pressure fluid upon the completion of its upstroke, the upper end of said piston having a greater cross-sectional area than the lower end thereof, whereby the pressure of said fluid will force the piston downwardly, and means carried by said piston and movable through said valve for actuating the valve to control the movement of the piston.

2. A hydraulic lifting mechanism including, a cylinder, a pressure responsive member movable in the cylinder having its lower end exposed to a pressure fluid for raising the same, means for admitting the fluid to the upper end of the member upon the completion of its upstroke so as to force the same downwardly, means for controlling the flow of fluid to the cylinder, means for

5 actuating the controlling means to restrict the flow of fluid therethrough as the member approaches the upper end of its stroke to cushion the upstroke thereof, and means for restricting the discharge of fluid from the lower end of said cylinder to cushion the downstroke of said member.

10 15 20 25 3. A hydraulic lifting mechanism including, a cylinder, a pressure responsive member movable in the cylinder having its lower end exposed to a pressure fluid for raising the same, means for directing a portion of the fluid to the upper end of the member upon the completion of its upstroke, the upper end of said member having a greater cross-sectional area than the lower end thereof, whereby the pressure of said fluid will force the member downwardly, means for restricting the flow of the fluid to the cylinder as said member approaches the upper end of its stroke to cushion the upstroke thereof, and means for restricting the discharge of fluid from the lower end of said cylinder to cushion the downstroke of the member.
